US00D785808S

(12) **United States Design Patent** (10) **Patent No.:** **US D785,808 S**
(45) **Date of Patent:** **** May 2, 2017**

(54) **COMBINED BASE AND STAND**

(71) Applicant: **Gulfstream Inc.**, Cambridge (CA)

(72) Inventor: **Minh Sang Tran**, Cambridge (CA)

(73) Assignee: **Gulfstream Inc.**, Cambridge, CA (US)

(**) Term: **15 Years**

(21) Appl. No.: **29/550,782**

(22) Filed: **Jan. 7, 2016**

(51) LOC (10) Cl. **23-02**

(52) U.S. Cl.

USPC **D24/204**

(58) **Field of Classification Search**

(57) **CLAIM**

The ornamental design for a combined base and stand, as shown and described.

DESCRIPTION

FIG. 1 is a front, left, top perspective view of the combined base and stand;

FIG. 2 is a rear, right, top perspective view of the combined base and stand;

FIG. 3 is a top view of the combined base and stand;

FIG. 4 is a bottom view of the combined base and stand;

FIG. 5 is a left side view of the combined base and stand;

FIG. 6 is a right side view of the combined base and stand;

FIG. 7 is a front view of the combined base and stand;

FIG. 8 is a rear view of the combined base and stand; and,

FIG. 9 is a front, left, top perspective view of the combined base and stand in its environment. The broken lines immediately adjacent the shaded area represent the bounds of the claim, while all other broken lines are directed to environment and are for illustrative purposes only; the broken lines form no part of the inventive design.

1 Claim, 8 Drawing Sheets
